(57) **CLAIM**

The ornamental design for a drawbar extrusion, as shown and described.

DESCRIPTION

FIG. 1 is a front perspective view showing my new design for a drawbar extrusion,

FIG. 2 is a rear perspective view,

FIG. 3 is an alternate front perspective view,

FIG. 4 is a top view,

FIG. 5 is a front view,

FIG. 6 is bottom view,

FIG. 7 is an end view, shown in a larger scale; and,

FIG. 8 is an opposite end view, shown in a larger scale.

The drawer extrusion is shown with symbolic breaks in its length. The appearance of any portion of the article between the break lines form no part of the claimed design.
